UNITED STATES PATENT OFFICE.

FRANK B. WHEAT, OF LOS ANGELES, CALIFORNIA.

SECTIONAL PARTITION OR PANEL STRUCTURE.

Application filed August 1, 1927. Serial No. 209,978.

This invention relates to partition or panel structures made up of a plurality of sections whose meeting edges are adapted to be concealed by separable pilasters, said sections and pilasters being so interlocked as to permit the same to not only be readily assembled, but to also permit them to be easily disassembled. For this reason the partition or panel structure contemplated in the present case might be said to be a portable one.

An object of the present invention is to provide a sectional partition wherein means are provided for holding the panels or partition sections in alignment preparatory to and while the pilasters are being placed against and locked to the sections.

Another object is to provide a novel form of locking means for holding the sections together and for locking the pilasters to the assembled sections. More specifically the locking means contemplated are of a nature that permits them to be loosely assembled in the partition or, in other words, they are held in place in the assembled partition without the need of attaching them by fastening elements such as nails, screws, or the like. In these respects, the present invention seeks to improve upon the partition structure shown in applicant's prior Patent No. 1,626,259, granted April 26, 1927.

In the accompanying drawings, Figure 1 is a vertical sectional view through the partition showing the pilasters locked in place.

Fig. 2 is a horizontal sectional view through a portion only of the partition showing the meeting edges of two sections with pilasters locked in place over the joint between their meeting edges.

Fig. 3 is a perspective view of the locking members, the locking member carried by the pilasters being shown detached therefrom.

Fig. 4 is a detail view of one of the locking members.

The partition may, of course, be of any desired length, but in the present instance it is only necessary to describe two juxtaposed sections in order to fully disclose the invention. In the accompanying drawings, the joint formed between the meeting edges of two juxtaposed sections 10 is adapted to be concealed by separable pilasters 11, 11^a, at opposite sides of the partition. Locking means for securing the pilasters to the two

sections are adapted to also serve the purpose of locking the two partition sections themselves together. In the present instance, this is accomplished by having locking elements on the pilasters engage one or more locking elements which extend between the two sections, the end portions of the latter being received in recesses in the pilasters so that when the parts are assembled the pilasters are held in position against the sections and the sections are held against separation by the locking element between them engaging in the recesses in the pilasters.

In the preferred construction, the pilasters are formed with recesses 12 extending vertically therein, and bridging said recesses throughout only a portion of their length are plates 13 which are adapted to engage over the hook-shaped terminals 14 of a locking plate or member 15 whose body portion is set in a recess in an edge of the panel 10 so as to lie flush with the edge surface thereof. One or more plates 15 are provided on each panel section and each pilaster carries a corresponding number of plates 13.

The plates 13 are attached to the pilasters by suitable fastening elements such as screws 16 but fastening elements may be dispensed with so far as the remaining locking elements are concerned. This is accomplished by means of plates 17 which lie between the hook-shaped terminals 14 of plate 15 and the side faces of the panel sections, said plates 17 being detachably secured to the sections, for instance, by being formed with offset end portions 18 which engage in recesses 19 in the side faces of the panel sections. Plates 17 are slotted as at 20 so that they can be slipped down over the body portion of plate 15. By having plate 15 seat in the recess in the edge of the panel and by having plates 17 secured in the recesses 19 in the panels, after being slipped down over the body portion of plate 15, the latter will be securely held in place. It cannot move vertically by reason of the end walls of the recess in which it is located and it cannot move laterally of the partition by reason of the plates 17 held in recesses 19.

This arrangement eliminates the use of fastening elements, such as screws, for all of the plates except the plates 13 which are attached to the pilasters. However, such

fastening elements may be used in the same arrangement although they are not indispensable.

By having plates 15 and 17 unattached, 5 these hardware fittings may be shipped separately from the partitions and pilasters and as plates 13 lie flush with the surface of the pilasters, neither the partition sections or pilasters have any projections which might 10 interfere with their packing or crating for shipments.

In assembling the partition sections, two sections are placed edge to edge with a plurality of plates 15 between said sections, 15 the hook-shaped terminals projecting at the sides of said sections. Plates 17 are then slipped in between the sections and each hook terminal of the several plates 15, the off-set ends 18 of the plates 17 being inserted 20 in slots 19 in the sections, said slots being sufficiently long to permit this. The plates 15 will consequently be locked in place, as previously described, after which nothing remains to be done except to position the 25 pilasters over the joint with plates 13 hooked over the hook terminals of plates 15.

What I claim is:

1. A sectional partition or panel structure comprising two juxtaposed sections, a pilaster separable from said sections and overlying the joint between the same, cooperating locking elements on said sections and pilaster for locking the pilaster to said sections, and means loosely assembled with said cooperating locking elements for holding the sections in alinement.

2. A sectional partition or panel structure comprising two juxtaposed sections having recesses in their side faces, a separable pilaster 40 overlying the joint between said sections, a plate between the meeting edges of the sections with hook-shaped terminals projecting beyond the sides of said sections, a plate between one of said hook terminals and projecting into the recesses in the side faces of the sections, and a plate on the pilaster engaging one of said hook terminals.

3. A sectional partition or panel structure comprising two juxtaposed sections having 50 recesses in the side faces, a separable pilaster overlying the joint between said sections, cooperating locking elements for locking the pilaster to said sections, and means loosely assembled with said locking elements and engaging in the recesses in said sections to hold the latter in alinement.

4. A sectional partition or panel structure comprising two juxtaposed sections having recesses in the side faces, a separable pilaster 60 overlying the joint between said sections, cooperating locking elements for locking the pilaster to said sections, said locking elements comprising a plate extending between

said sections with hook-shaped terminals projecting beyond the sides of the sections, 65 plates between said hook terminals and the sections, said last mentioned plates having their ends engaged in the recesses in the side faces of said sections.

5. In a sectional partition or panel structure comprising two juxtaposed sections having recesses in the side faces, a separable pilaster overlying the joint between said sections, cooperating locking elements for locking the pilaster to said sections, said locking elements comprising a member 70 between said sections with hook-shaped terminals projecting beyond the sides of the sections, and plates between said hook terminals and sections, said plates engaging in the recesses in the sides of the sections and having slots therein for the reception of said hook-shaped locking member.

6. A sectional partition or panel structure comprising two juxtaposed sections having 75 recesses in their side faces and a recess in one of the meeting edges, a locking member lying in said edge recess and having hook-shaped terminals projecting beyond the sides 80 of said sections, a separable pilaster at each side of the partition overlying the joint between the meeting edges of said sections, locking elements on said pilasters engaging said hook terminals, and plates between said hook terminals and sections formed with 85 offset end portions engaging in the recess in the sides of the sections.

7. A sectional partition or panel structure comprising two juxtaposed sections having recesses in their side faces, a separable pilaster at each side of the partition overlying the joint between said sections, a locking member lying between the sections, a cooperating locking member on each pilaster, and a plate at each side of the partition engaging the 100 locking member between the sections for preventing movement of the same laterally of the partition, said plates having projections at their ends engaging in the recesses in the side faces of the sections.

8. A sectional partition or panel structure, comprising two juxtaposed sections, a separable pilaster at each side of the partition overlying the joint between said sections, a locking member lying between the sections, a 105 cooperating locking member on each pilaster, and a plate at each side of the partition engaging the locking member between the sections for preventing movement of the same laterally of the partition, said plates being connected to said sections and preventing movement of said sections away 110 from each other while the pilaster are being locked to the partition.
